PAGE 2

FIG. 2.

FIG. 3.

FIG. 4.

FIG. 5.

FIG. 1 is a perspective view of a video signal generating keyboard showing my design;

FIG. 2 is a top plan view thereof;

FIG. 3 is a right side elevational view;

FIG. 4 is a right side elevational view, the left side being a mirror image thereof; and

FIG. 5 is a front elevational view thereof.

I claim:

The ornamental design for a video signal generating keyboard as shown and described.
